UNITED STATES PATENT OFFICE.

JAMES A. NELL, OF NEW BRITAIN, CONNECTICUT.

SURFACE AND CENTER INDICATOR.

1,380,580.

Specification of Letters Patent. Patented June 7, 1921.

Application filed March 25, 1919. Serial No. 284,925.

To all whom it may concern:

Be it known that I, JAMES A. NELL, a citizen of the United States, and a resident of New Britain, in the county of Hartford, and State of Connecticut, have invented 5 certain new and useful Improvements in Surface and Center Indicators; and I do hereby declare the following to be a full, clear, and exact description of the invention, such as will enable others skilled in the art to which it appertains to make and use the same.

This invention relates to improvements in surface and center indicators,—one object 15 of the invention being to provide an efficient instrument for ascertaining the variations of a given plane, arc or center of mechanical and structural objects, and to combine the feature of a surface and center indicator 20 in compact and useful form.

A further object is to provide simple and efficient means for securing the instrument to suitable tool posts or other fixtures to enable the operator to readily adjust the 25 instrument with the dial in position for easy observation.

With these and other objects in view the invention consists in certain novel features of construction and combinations of parts 30 as hereinafter set forth and pointed out in the claims.

In the accompanying drawings; Figure 1 is a view in elevation of an instrument embodying my invention; Fig. 2 is a view in 35 section on the line 2—2 of Fig. 5; Fig. 3 is a view in section on the line 3—3 of Fig. 5; Fig. 4 is a view in section on the line 4—4 of Fig. 5; Fig. 5 is a sectional view on the line 5—5 of Fig. 1; Fig. 6 is a plan 40 view of the lower casing member; Fig. 7 is a view in section on the line 7—7 of Fig. 6; and Figs. 8, 9, 10, 11 and 12 are detail views.

1, 2 represent upper and lower frame casting members respectively, which are superimposed one upon the other and formed with openings of irregular shape to accommodate the mechanism of the instrument. The respective frame members 1, 2 are made 45 with mating grooved arms as indicated at 3 to form a rod-bearing as hereinafter explained and with spaced arms or fingers 4—4 between which a contact element is movable and by which said element is protected.

A plate 5 having a configuration corre-

sponding with that of the irregular opening in the lower frame plate 2 enters said irregular opening and a similarly-shaped plate 6 is located in the irregularly-shaped opening of the upper frame plate 1,—the irregularly-shaped plates 5 and 6 being so disposed relatively to each other as to leave space between them for the accommodation of parts of the mechanism mounted on the lower plate 5. A dial plate 7 is located over the upper plates 1 and 6, and a frame 8 spaces a transparent disk 9 and a top plate 10 from the dial plate 7,—said top plate having an opening 11 through which the dial plate and a pointer which co-operates therewith can be seen. A base plate 12 is provided for the instrument, and fastening devices such as indicated at 13 serve to secure the several parts of the casing or framework in assembled position.

A lever 14 (which constitutes a contact member) is pivotally mounted on a pintle 15 on the plate 5 and the forwardly projecting arm of this lever is made with a head 16 having three contact portions *a, b, c*. The member or portion 17 of the lever, which extends rearwardly of the pivotal mounting 15, is disposed between the plates 5—6 and is provided at its rear end with 85 a hook-shaped arm 18,—the portion 17 of said lever being also provided, intermediate of its ends, with a V-shaped tooth 19 and a V-notch 20.

A lever 21 is mounted on a pintle 22 on 90 the plate 5 and at one side of its pivotal mounting, said lever is provided with a tooth 23 in position to be engaged by the free end of the arm 18 of the lever member 17. At the free end of the long arm of the lever 21, a toothed segment or rack 24 is provided and meshes with a pinion 25. A pintle 26 is provided on the plate 5 for the accommodation of the hub of the pinion 25 and to said hub, a pointer 27 is attached and 100 adapted to co-operate with the scale on the dial plate 7. A spring 28 (Fig. 2) encircles the hub of the pinion 25 and is attached at one end to a pin 29 on said pinion, the other end of said spring being attached to a pin 105 30 on the plate 5 and thus serving to retain the parts in and return them to their normal positions.

A bell-crank lever 31 is mounted on a pintle 32 on the plate 5 and a sliding bar 33 110 is located between the plates 5 and 6 and guided in notches in the plates 1 and 2 as

indicated at 34—35. The bar 33 is provided with a rod 36 which is slidingly mounted in the bearing formed by the grooves in the arms 3 of the framework and to the free end of this rod, a knob 37 is secured. The longitudinal movement of the bar 33 and its rod 36 is limited by a pin 38 which passes transversely through a groove 39 in said rod as shown in Fig. 3. The bar 33 is made 10 at one end with an enlargement 40 having a V-notch 41 in which one pointed end of a rod 42 has a bearing, the other pointed end of said rod having a bearing in a V-notch 43 near the free end of the arm 44 of the 15 bell-crank lever 31. The arm 45 of the bell-crank lever is provided near its free end with a V-notch 46 into which one pointed end of a rod 47 has a bearing, the other pointed end of this rod having a bearing in the 20 V-notch 20 of the lever member 17. The rods 42 and 47 are notched where they pass each other as at 48 (Figs. 9 and 10) to avoid conflict with each other and the bar 33 is notched as at 49—50 for the accommodation 25 of the rod 47 and the arm 44 of the bell-crank lever.

Stop pins *d* may be employed for limiting the movements of the pivoted parts of the instrument.

30 A shank 51 is secured to the base plate 12 of the instrument and provided with a ball-head 52 and to effect a universal coupling between this headed shank and a rod 53 to be secured to a tool post or other part of a 35 machine, the coupling devices now to be described will be found efficient. A plate 54 having a socket near one end to receive the ball head 52 and a socket near its other end to receive a ball-head 55 on the rod 53, is 40 provided and the ball heads are retained in said sockets by a plate 56. A screw 57 passes freely through a hole in the plate 54 and is threaded through the plate 56, whereby the ball-heads 52 and 55 may be clamped 45 between said plates. Guide pins 58 are secured to the plate 54 and pass freely through holes in the plate 56. By means of these coupling devices, the instrument may be adjustably connected with a machine and readily manipulated when in use.

50 The operation of the instrument is as follows: After attaching the instrument through the coupling devices, to a suitable support, such for example, as the tool post of a lathe, shaper or other machine, one of the contact portions *a*, *b*, *c* or 37 will be brought in contact with the surface to be tested. If the portion *b* of the contact head 16 be used, the lever 14 will be moved in the direction of *c*, and the portion 17 of said lever will move 55 in the reverse direction, thus causing the lever 21 to be turned on its pivotal support and impart motion to the gear 25 in clockwise direction and causing movement of the pointer 27 relatively to the scale. When the

pressure of the lever 14 against the work is withdrawn, the spring 28 will return the pointer and the parts which actuate it, to normal positions. Should the contact portions *c* of the head 16 be used in testing a 70 surface, the lever 14 will be moved in the opposite direction and the tooth 19 on the portion 17 of said lever will cause the lever 21 to be moved and movement to be imparted to the pointer in the same direction 75 as previously described.

To ascertain the accuracy of the center of a piece held in a chuck or on a face plate of a machine, the point *a* of the contact head 16 will be inserted into the center mark; then 80 pressure will be applied to move the lever in either direction *b* or *c* until the pointer registers zero on the scale and then revolve the piece and the eccentricity of the center mark will vibrate the lever 14 and the pointer will 85 be moved accordingly.

The pointed contact head is admirably adapted for use in entering small holes, centers or narrow spaces, but where space is less limited, the knob or contact head 37 may be 90 employed, and in such case, the instrument would be operated as follows: Pressure applied at 37 will cause longitudinal movement of the bar 33, and this movement will be transmitted by the rod 42 to the bell-crank 95 lever 31, and movement of the latter will be transmitted by the rod 47 to the portion 17 of the lever 14. Such movement of the lever 14—17 will be transmitted by the tooth 19 to the lever 21 and movement of the latter will 100 cause movement of the pointer through the medium of the rack-and-pinion gearing.

Various slight changes might be made in the details of construction of my invention without departing from the spirit thereof or 105 limiting its scope and hence I do not wish to restrict myself to the precise details herein set forth.

Having fully described my invention what I claim as new and desire to secure by 110 Letters-Patent, is:—

1. In a device of the character described, the combination with a frame, a pointer, a spring for retaining said pointer in and returning it to normal position, a pivoted lever, 115 and means between said pivoted lever and pointer for transmitting movement to the latter, of a second lever cooperating with said first-mentioned lever, a sliding bar, a bell-crank lever, a rod having pivotal connection with said bar and with one arm of the bell-crank lever, and a rod having pivotal connection with the other arm of said bell-crank lever and said second lever. 120

2. In a device of the character described, the combination with a frame, a pointer, a spring for retaining said pointer in and returning it to normal position, a pivoted lever, and means between said pivoted lever and 130

pointer for transmitting movement to the latter, of a second lever coöperating with said first-mentioned lever at respective sides of the fulcrum of the latter and provided with 5 a contact portion, a sliding bar, a bell-crank lever, a rod between said sliding bar and one arm of the bell-crank lever, and a rod between the other arm of said bell-crank-lever and said second lever.

- 10 3. In a device of the character described, the combination of a frame comprising plates having openings therein, other plates mounted in said openings, a dial plate on said frame and a top plate over the dial 15 plate and having an opening through which the dial plate may be viewed, of a lever piv-

oted between said other plates and provided with a contact head, a pointer coöperable with the dial of said dial plate, a spring for retaining said pointer in and returning it to 20 a normal position, and mechanism between said other plates for transmitting movement of said lever and its contact head to said pointer.

In testimony whereof, I have signed this 25 specification in the presence of two subscribing witnesses.

JAMES A. NELL.
